Nelson M. Howard

UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Original application filed April 22, 1922, Serial No. 556,063. Divided and this application filed April 16, 1927. Serial No. 184,394.

This invention relates to machines for shaping uppers over lasts in the manufacture of boots and shoes, and more particularly to means for controlling the insole on the last, this application being a division of a copending application, Serial No. 556,063, filed on April 22, 1922, which has resulted in Letters Patent No. 1,667,789, granted on May 1, 1928. The invention is herein illustrated in its application to a machine for pulling uppers over lasts, but it will be recognized that in its more general aspects the invention is not limited to pulling-over machines. The present invention is especially useful in its application to machines for pulling-over or lasting tennis shoes or the like, although not necessarily limited to that use. Shoes of that type usually have insoles of rubber composition which are comparatively soft and yieldable and are, therefore, liable to become wrinkled or otherwise displaced on the last. It has been found that such wrinkling or displacement of a portion of the insole may occur, for example, in the pulling-over operation by reason of the pressure on the insole of the several sole rest feet with which pulling-over machines are customarily provided or by reason of a slight relative displacement of the last and the sole rest feet that may occur when the upper is pulled by the grippers. As a result, a portion of the insole near its edge may be lifted or curled away from the bottom face of the last, so as to interfere with the proper laying of the upper inwardly over the insole. This invention accordingly provides novel means for correcting such a condition when it occurs. The construction shown as an illustrative embodiment of the invention comprises manually operative means for effecting relative movement of the several sole rest feet of a pulling-over machine both lengthwise and widthwise of the last to straighten the insole after the upper has been subjected to tension by the pulling means. The construction shown further includes means for retaining the sole rest feet in the positions to which they are moved in straightening the insole, and automatic means for returning them eventually to their starting positions.

The invention will now be more particularly described by reference to the accompanying drawings and thereafter pointed out in the claims.

In the drawings,

Fig. 1 shows partly in side elevation and partly in section a portion of a pulling-over machine in which the invention is embodied;

Fig. 2 is substantially an inverted plan view of the sole rest, on a scale larger than that of Fig. 1, with parts broken away, and

Fig. 3 is a view in side elevation of a part of the means provided for controlling the sole rest feet.

Since the machine in which the invention is herein shown as embodied is of a well-known type characteristic features of which are described in various prior United States Letters Patent, including Letters Patent No. 1,029,387 granted on June 11, 1912, upon an application of R. F. McFeely, and also in the copending application hereinbefore mentioned, only such parts will be herein described in detail as are intimately related to the features of this invention. It will be understood that, in operating on tennis shoes or the like, a last with an upper thereon and with an insole of rubber composition loosely mounted on its bottom face is presented to the machine, and that the margin of the upper is then engaged by a toe gripper 10 and by opposite side grippers, one of which is shown at 12, and is pulled to shape the upper tightly over the last, after which the machine comes automatically to a stop with the upper held under tension, as illustrated in Fig. 1. The last is supported against the pull of the grippers by a sole rest, which as herein shown comprises a pair of feet 14 arranged to engage the insole at the opposite sides of the forepart at the rear of the toe and another foot 16 arranged to engage it centrally near the toe end of the last the different feet having teeth or serrations thereon for engaging the bottom face of the insole. The feet 14 and 16 are supported on a carrier 18 which in the upper-pulling operation of the grippers is swung downwardly a short distance by a cam 20 in engagement with a roll 22 on the carrier to depress the forepart of the last and thereby assist in the pulling of the upper.

It has been found that in this upper-pulling operation effected by the combined movements of the grippers and the sole rest there sometimes results a wrinkling or curling up of a portion or portions of the insole near its edge, due to the pressure of the sole rest feet thereon and to a slight shifting or twisting movement of the last relatively to the sole rest that may occur when the upper is pulled by the grippers. By the present invention there is provided means for correcting such a condition by straightening the insole through relative movement of the different sole rest feet lengthwise and widthwise of the last. For this purpose the side feet 14 are mounted on the front ends of arms 24 which are mounted to turn about pivot studs 26 carried by a bracket 28 fast on the carrier 18, and the front foot 16 is supported on a bar 30 which is adjustably secured to a holder 31 mounted in the carrier 18 for sliding movement lengthwise of the shoe relatively to the bracket 28. A spring 32 tends, as in prior constructions, to maintain the holder 31 in a retracted position, and for moving it forwardly against the resistance of the spring a pinion 34 is provided in engagement with rack teeth 36 on the holder, the pinion being formed on a shaft 38 (Fig. 3) to which is secured a hand lever 40. Secured to the holder 31 is a plate 42 which carries a pin 44 projecting into slots 46 formed in the rear ends of the arms 24. When forward movement is imparted to the holder 31 by the hand lever 40, the pin 44 will thus act to swing the arms 24 in directions such as to separate the side feet 14 while the front foot 16 is being moved forwardly by the forward movement of the holder. In this manner the forepart of the insole may be straightened on the last, if necessary, so that all portions of it will lie close to the bottom face of the last, while the machine is at rest after the upper-pulling operation.

There is further provided means for holding the different sole rest feet in the positions to which they are moved by the hand lever 40, comprising a spring-controlled pawl 48 (Fig. 3) arranged to engage a ratchet wheel 50 fast on the shaft 38. In order that the sole rest feet shall be returned automatically to their starting positions by the action of the spring 32 on the holder 31 after the operations on the shoe have been completed, the pawl 48 is further controlled by a releasing member 52 carried by a slide 54 which is a characteristic element of machines of the type illustrated. It will be understood that early in the cycle of the machine the slide 54 is moved toward the left (Fig. 3), thus releasing the pawl 48 to permit it to engage the ratchet wheel 50 and thus to perform its holding function when the hand lever 40 is operated, and that

in the latter part of the last stage of the cycle of the machine the slide is moved toward the right and thus causes the member 52 to engage the pawl and to disconnect it from the ratchet wheel, as illustrated in Fig. 3.

Having described the invention, what I claim as new and desire to secure by Letters Patent of the United States is:—

1. In a machine of the class described, the combination with means for pulling an upper over a last having an insole thereon, of a sole rest comprising a plurality of members for engaging the insole respectively in different locations over the bottom of the last, and means for effecting relative movement of said members both lengthwise and laterally of the last to straighten the insole on the last while the upper is held under tension by the upper-pulling means. 75

2. In a machine of the class described, the combination with means for pulling an upper over a last having an insole thereon, of a sole rest comprising members for engaging the insole respectively in different locations widthwise of the last, and means for moving said members apart to straighten the insole on the last while the upper is held under tension by the upper-pulling means. 90

3. In a machine of the class described, the combination with means for pulling an upper over a last having an insole thereon, of a sole rest comprising members for engaging the insole respectively at opposite sides of the forepart and a member for engaging the insole nearer the toe end of the last than said first-named members, and means for moving said first-named members outwardly toward the sides of the last and for moving said last-named member forwardly to 105 straighten the insole on the last while the upper is held under tension by the upper-pulling means. 100

4. In a machine of the class described, the combination with means for pulling an upper over a last having an insole thereon, of a sole rest comprising a plurality of members for engaging the insole respectively in different locations, manual means for effecting relative movement of said members both lengthwise and laterally of the last to straighten the insole on the last while the upper is held under tension by the upper-pulling means, mechanism for retaining said members in the positions to 115 which they are thus moved, and automatic means for subsequently returning said members to their initial positions. 120

5. In a machine of the class described, the combination with means for shaping an upper over a last having an insole thereon, of a sole rest comprising a carrier and members supported thereon for engagement with the insole respectively in different locations over the bottom of the last, and 130

- mechanism connected to said members for moving them relatively apart both lengthwise and laterally of the last while in engagement with the insole to straighten 5 the insole on the last.
6. In a machine of the class described, the combination with means for shaping an upper over a last having an insole thereon, of a sole rest comprising a carrier and a 10 plurality of insole-engaging members supported thereon comprising members for engaging the insole respectively in different locations widthwise of the last and a member for engaging the insole nearer the toe 15 end of the last than said first-named members, and mechanism connected to said members for moving the first-named members outwardly toward the sides of the last and for moving the last-named member 20 forwardly while in engagement with the insole to straighten the insole on the last.
7. In a machine of the class described, the combination with means for shaping an upper over a last having an insole thereon, 25 of a sole rest comprising a member for engaging the insole near the toe end of the last and additional members for engaging the insole respectively at opposite sides of the forepart, and mechanism connected to 30 said different members for moving said toe end member forwardly and said additional members widthwise of the last to straighten the insole on the last.
8. In a machine of the class described, the 35 combination with means for shaping an upper over a last having an insole thereon, of a sole rest comprising a member for engaging the insole near the toe end of the last, additional members for engaging the 40 insole respectively at opposite sides of the forepart, said additional members being pivoted for swinging movements widthwise of the last, and means for simultaneously moving said toe end member forwardly 45 and swinging said additional members apart while the members are in engagement with the insole.
9. In a machine of the class described, the 50 combination with means for shaping an upper over a last having an insole thereon, of a sole rest comprising a member for engaging the insole near the toe end of the last and additional members for engaging the 55 insole respectively at opposite sides of the forepart, said additional members being pivoted for swinging movements widthwise of the last, means for moving said toe end member forwardly, and pin and slot connections 60 between said toe end member and said additional members for swinging the latter apart during the forward movement of the toe end member.
10. In a machine of the class described, the combination with means for shaping an upper over a last having an insole thereon, 65 of a sole rest comprising members for engaging the insole respectively at opposite sides of the forepart, said members being pivoted for swinging movement widthwise of the last and having teeth for engaging 70 the bottom face of the insole, and manually operated means connected to said members for swinging them apart while they are in engagement with the insole to straighten the 75 insole.
11. In a machine of the class described, the combination with means for shaping an upper over a last having an insole thereon, 80 of a plurality of members having serrated portions arranged to engage the insole in different locations widthwise of the last, and means for effecting relative movement of said members widthwise of the last to straighten the insole.
12. In a machine of the class described, 85 the combination with means for shaping an upper over a last having an insole thereon, of a plurality of members for engaging the insole, and means for effecting relative movement of said members both lengthwise and 90 widthwise of the last to straighten the insole.
13. In a machine of the class described, the combination with means for shaping an upper over a last having an insole thereon, 95 of a member arranged to engage the insole near the toe end of the last, other members arranged to engage the insole at the sides of the forepart at the rear of said first-named member, and manually operated means for moving said first member forwardly and for 100 spreading said other members apart to straighten the insole.
14. In a machine of the class described, the combination with means for shaping an upper over a last having an insole thereon, 105 of a member arranged to engage the insole near the toe end of the last, other members arranged to engage the insole at the sides of the forepart at the rear of said first-named member, manual means for moving said first member forwardly and for spreading 110 said other members apart to straighten the insole, mechanism for retaining said members in the positions to which they are thus moved, and automatic means for subsequently releasing said members and returning them to their initial positions. 115

In testimony whereof I have signed my name to this specification.

BERNHARDT JORGENSEN.
